United States Patent Office.

JAMES SHEPARD, OF BRISTOL, CONNECTICUT.

Letters Patent No. 78,021, dated May 19, 1868; antedated May 7, 1868

IMPROVEMENT IN MACHINE FOR WIRING PANS.

The Schedule referred to in these Letters Patent and making part of the same.

TO ALL WHOM IT MAY CONCERN:

Be it known that I, JAMES SHEPARD, of Bristol, in the county of Hartford, and the State of Connecticut, have invented a new and improved Tinsmiths' Machine for Wiring Square Pans; and I do hereby declare that the following is a full, clear, and exact description thereof, which will enable others skilled in the art to make and use the same, reference being had, to the accompanying drawings, forming part of this specification, in which—

Figure 1 is a perspective view of my invention.

Figure 2 is a front elevation of the two rollers.

Figure 3 is a side elevation of the same.

Similar letters of reference indicate like parts.

My invention consists in the use or employment of a square roller, die, or swage, fitted to revolve in a suitable frame immediately beneath a round roller with a narrow edge, like the upper roller of a common wiring-machine.

A designates the square roller, die, or swage.

B designates a pin, on which the square roller, die, or swage, A, revolves.

C designates the frame.

D designates the upper roller.

E designates a spring, for raising the upper roller, D.

F designates a shaft, to which the upper roller, D, is secured.

G designates a crank, for turning the shaft F with the upper roller, D.

H designates a pivoted or hinged box, in which one end of the shaft F revolves.

I designates a half box over the other end of the shaft F.

J designates a follower, for lowering the box I with the shaft F and the upper roller D.

L designates a lever, for operating the follower J.

M designates a gauge, for guiding the edge of the pan.

N designates a screw, for adjusting the gauge M.

O designates a section of metal formed around the wire.

P designates a section of the wire.

Q designates a cord or rope, for operating the lever L.

The cord or rope, Q, should be connected with a lever under the tinsmith's bench, so that the upper roller, D, can be readily operated with the foot of an operator. The square roller, die, or swage, A, should have a small bead on its front edge precisely the same shape as the bead on the lower roller of a common wiring-machine. It should be placed exactly below the centre of the upper roller, D, as shown in fig. 2.

The two rollers should be so arranged that, when they are brought together, the thin edge of the upper roller, D, and the bead of the square roller, die, or swage, A, should nearly meet, the thin edge of the upper roller, D, slightly projecting to the front, as shown in fig. 3.

It will be seen at a glance that if the upper roller, D, is brought in contact with the square roller, die, or swage, A, when one of its straight edges lies horizontally, as shown in fig. 2, it cannot revolve unless the upper roller, D, is raised.

To use my machine, take a square pan that has been formed and the metal turned on the edge, preparatory to receiving the wire, and place the wire in its intended place. Set the gauge M at a distance from the beads of the two rollers to correspond with the diameter of the wire and thickness of the metal, as shown in fig. 3. Place the edge of the pan against the gauge M, with the inside of the pan over the square roller, die, or swage, A, and bring down the upper roller D. With the right hand turn the crank G, and at the same time pull the pan towards you, with the left hand, when it will slide over the square roller, die, or swage, and move with the circumference of the upper roller, D, until the square roller, die, or swage, A, is in the corner of the pan.

Then revolve the pan-one-fourth of a revolution, and the square roller, die, or swage, A, will revolve with it. When the operator revolves the pan with the lower square roller, die, or swage, A, he must allow the upper roller, D, to rise a little, but must keep sufficient pressure on it to swage the metal around the wire. After the upper roller, D, has passed the corner of the pan, bring it down again, and proceed in like manner around the pan.

If a three-square or other shaped pan is desired to be wired, simply make the lower roller, die, or swage, A, to correspond with the shape of the pan to be wired.

The ordinary wiring-machine is designed only for straight and round work. It consists of two round rollers, generally about three inches in diameter, with a bead on the front edge of both, and both rollers firmly secured or welded to suitable shafts, which shafts are provided with gearing, and properly adjusted in a suitable frame. It is evident that this machine cannot wire the square corner of a pan, but sometimes it is used for partly wiring square pans by first wiring one side, as near the corner as they can, and then taking it out of the machine, and putting it in again to wire another side, and so on, making four times that one pan has to be put in the machine, and then the corners are finished with the pene of a hammer.

Other tinsmiths wire the pans entirely with the pene of the hammer, while others use a square pan-swage, which is nothing more than a hinged hammer.

By my invention, I produce a machine for wiring square pans which will finish a pan without taking it from or stopping the machine. It forms the metal, even in the extreme corners, firmly around the wire. It performs its work much better and nicer than it can be done by any other known mode. It is simple in construction, requires no geared wheels, and can, consequently, be made at a very low price. It is the only machine known to the makers of tinsmiths' machines in this country for doing the same work, and is supposed to be the only one in the world.

I do not claim the lever L, for lowering the upper roller, D; neither do I claim the roller, D, the frame C, or the gauge M; but

What I do claim as new, and desire to secure by Letters Patent, is—

The combination of the roller-die, D, with the revolving die, A, constructed and operating as described.

JAMES SHEPARD.
